UNITED STATES PATENT OFFICE.

FRANK F. LANDIS, OF WAYNESBORO, PENNSYLVANIA.

SHOCK DIFFUSER.

Application filed November 13, 1924. Serial No. 749,760.

To all whom it may concern:

Be it known that I, FRANK F. LANDIS, a citizen of the United States, residing at Waynesboro, in the county of Franklin and State of Pennsylvania, have invented certain new and useful Improvements in Shock Diffusers, of which the following is a specification.

My said invention relates to a shock diffuser and it is an object of the same to provide an improved hydraulic apparatus of the character described in which oil may be used but where no frothing or foaming of the oil shall occur during violent operation of the device, therefore no mulching of the oil.

The invention is janus-faced, all work strains being equally divided by a common center. The same unit is attachable at the right or left and back or front of the body of an automobile. There is no waste of oil, no packed joints are required, no adjustments are required to accommodate a light or heavy load, the action is silent, and the device is light in weight, small in bulk, inconspicuous, and quickly accessible for inspection without the use of tools.

Referring to the accompanying drawings, which are made a part hereof and on which similar reference characters indicate similar parts,

Fig. 1 is a vertical section of my device;

Figure 2, a vertical section at right angles to Figure 1;

Figure 3, a section on line 3-3 of Figure 1;

Figure 4, a vertical section of an oiling device shown in Figure 1;

Figure 5, a section on line 5-5 of Figure 1,

Figure 6, a fragment of the connection between a piston and a rocker arm, shown in Figure 1, and

Figure 7, a fragmentary elevation of a connecting rod attached to the vehicle axle or any unsprung part of an automobile taken at right angles to the position of Figure 1.

In the drawings reference character 10 indicates a housing adapted to be attached to the right or left back or front end of a vehicle frame by anchor bolts passing through holes at 11 and 12. The housing is open at its lower end and preferably slightly tapered to form a seat for the upper margin of a container or tank 13 for

liquid (preferably oil), the preferred upper level of said liquid being indicated at 14.

The slightly tapered lower end of housing 10 and the upper margin of the container 13 form a slip joint around the lower end of 10 and a bail 16 pivoted at 17 is arranged to extend under the liquid container 13 and lengthwise thereof for holding the same in place. It will be seen that the bail can easily be swung to one side whereupon the tank may be detached by a downward pull as for replenishing the oil or inspecting interior details.

A pair of bolts 18 have threaded engagement with the housing 10 and extend downward therefrom nearly to the bottom of the tank. These bolts support a cross-head 19 by means of nuts on the respective bolts and the cross-head has a piston 20 pivoted thereon at 21 midway between said bolts. This joint will never produce a rattle since gravity acting on the parts holds the parts down in the same direction as the action of the force of a spring recoil. The piston has an apertured head in which is situated a large and free intake valve 21 having a depending stem 22 with a pin 23 extending crosswise thereof near its lower end. A sleeve 24 is supported by the pin, said sleeve having an outwardly extending flange at its lower end. A spring 25 rests on said flange and at its upper end bears resiliently against a bowed cross bar 26. Said crossbar at its ends bears against the underside of the surface around the valve opening at the upper end of piston 20, and the spring presses downward on the valve stem through the sleeve 24 to reinforce the action of gravity

or to quicken the closing movement of the valve 21 on its seat before the automobile spring starts to recoil. I have found that with low oil temperatures, the gravity of valve 21 during certain spring movement was not sufficient to close the valve promptly enough to seat it before the start of automobile spring recoil and on that account caused a slight jar after the start of recoil.

The housing has near its upper end a pair of bearings 27 (Fig. 2) supporting a pair of journals 28 for oscillatory movement. The journals have longitudinal apertures for a pair of pins 29 extending at their outer ends into a pair of levers 30, 31. A bolt 32 extends axially through the journal and through said levers said bolt having washers

33 at opposite ends which are large enough to extend partially over the ends of the pins 29 so that when the nut on said bolt is screwed down the pins are fixed securely in 5 place. To keep dust out of the journal, a pair of flanged disks 34 are mounted on opposite ends of the journal under the working ends of levers 30 and 31, the flanges of said disks fitting about annular enlargements 10 around the said bearings 27, and their outside diameter being finished concentric with said bearings on opposite sides of the housing. Said disks 34 are perforated to receive said pins 29 and said bolt 32.

15 A rockarm 35 is positioned between the journals 28, said rockarm having apertures for the pins 29 and the bolt 32 whereby it is held in fixed relation to the levers 30, 31. The rockarm comprises a disk of slightly 20 larger diameter than the journals 28 and has an extension at one side provided with an aperture in which is supported with a pressed fit a pin 36 by which the forked stem 37 which projects from the upper and 25 closed end of an inverted cylinder 38 is pivotally connected to the rockarm. In order to avoid lost motion between the pin 36 and the bearings in the forked ends of stem 37, a bent leaf spring 39 is employed (Figs. 30 1, 3 and 6) which is secured at its upper end to a pin 40 the ends of which are supported in apertures in projections on the stem 37, while the other end of said spring is bent to conform to the contour of the upper side of 35 the rockarm whereby the spring will tend to force the rockarm and pin 36 down and the stem 37 upward which is the same direction in which the force of the recoil will move the parts, thereby avoiding all possibility of the connection between 37 and said 40 rockarm 35 causing a rattle, if the pin 36 is not a perfect working fit in the bearings through the forked end of 37. Even if such joints be perfect when constructed they will 45 always by use soon acquire sufficient looseness to cause lost motion and a rattle, and this is what is avoided by my construction.

The outer ends of the levers 30, 31 are 50 connected to a part 41 which is secured in any suitable manner to the axle or other unsprung part of the running gear, by a rod 42 threaded at one end for connection to a cap 43 through which a pin 44 passes (Figs. 1 and 3) said pin extending at its ends into 55 holes in the outer ends of levers 30 and 31 so providing a pivotal connection between the rod and said levers. A lock-nut 45 prevents the screw end of 42 from loosening in the lower and tapped end of 43. A short 60 cylindrical plug 46 is inserted in an aperture in the cap and has a concave face bearing against the cross-pin 44. A spring 47 presses the plug 46 against the cross-pin with sufficient force to maintain a constant bearing 65 or contact of pin 44 against the upper side

of the hole across the upper end of cap 43, which is the position it holds during auto spring recoil, preventing any possibility of a rattle as with a loose joint.

At its lower end the rod 42 is pivotally 70 connected to a foot-piece 48. A recess in the foot-piece opens upward and a spring 50 in the recess presses a plug 51 against the lower end of the rod 42 thereby holding pin 52 in constant contact with the rod 42 and the 75 foot-piece 48 in the direction they always are during automobile spring recoil. The springs 47 and 50 are so arranged as to insure constant contact between the pins 44 and 52 and the parts in engagement therewith in the direction they are in contact when a spring recoil occurs, or at the side where the pull of the automobile spring recoil causes the attached parts to bear against the pins. By the arrangement described for 80 the pins 36, 44 and 52 all lost motion in connection with a spring recoil is effectively prevented and thus there is no chance of a rattle at any place due to a loose joint. The only point within the casing where a rattle 85 would be likely to occur in the absence of special precautions is at pivot 36 and this effect is precluded by the use of spring 39. All lost motion in the connecting joints between the forked stem 37 and the foot piece 90 48 is eliminated by this construction, leaving only positive connections in one direction, which is the direction they are operating during all automobile spring recoil movements.

In my previous constructions of hydraulic means for governing automobile spring actions, the major difficulty has been caused by violent agitations on the top surface of the main body of oil in the retainer or tank 13, causing it to froth producing internal pressure which caused extravagant waste of the oil, within and around the main bearings and journals 27 and 28, which were always excessively lubricated, causing much waste 105 of oil and very frequent refilling, but with my present construction there is no agitation on top surface of the oil in retainer 13. Experience so far with my present construction indicates that capillary attraction, that is the oil creeping up the sides of the inner surface of the housing 10, lubricates the journals 28 and bearings 27 sufficiently to prevent abrasion of either the journals or their 110 bearings.

In case such lubrication should not be sufficient, due to long continuous action or to heavy oil, I have provided a simple automatic means for supplying additional oil to that brought by capillary attraction to the 115 journals without excessive waste of oil through bearings 27. Such means comprises a pipe 53 secured near its lower end to a bolt 18 by means of an apertured plate 54 or other convenient form of holding device, 120 125 130

said plate in this instance being held in place by a set screw 55. The pipe is bent sharply at its lower end to provide a funnel 56 (Figs. 1, 4 and 5) which funnel is approximately 5 in the path of a violent movement of oil as it emerges from the lower end of a bypass pipe 59 which is beneath the surface of the liquid in the tank. The upper end of this pipe communicates with the upper and 10 closed end of an inverted cylinder 38.

When violent recoil of automobile springs occurs, the downward current of oil from the lower end of bypass pipe 59 is by its momentum sufficient during violent automobile 15 spring recoils to occasionally deliver a few drops of oil up through pipe 53 into or above the lip 57 in the upper end of housing 10. From the bottom of the trough formed by lip 57 the oil gravitates through 20 small oil holes 58 leading to the upper surface of the journals 28. The value of the bypass 59 is due to the fact that a limited amount of oil remains between the inverted cylinder and the piston at the upper end 25 of the cylinder even when the movements of the cylinder reach the maximum. This oil is not circulated with the remainder of the oil in the retainer 13 in the absence of the bypass 59 but remains in the upper end 30 of the cylinder and becomes heated due to the continuous succession of impulses of the shock diffusing elements and the high pressure. Under these conditions it forms a gas in the upper end of the cylinder 38. 35 Such a gas is necessarily elastic and offers no effective resistance at the start of the recoil of the automobile springs since the gas must first be compressed by such movement. Hydraulic resistance is not established 40 to govern the spring recoil until the stored force in the automobile spring is multiplied by the speed, which being suddenly checked produces a jar, after the start of all automobile spring recoil movements. In other 45 words, if means are provided to reduce the speed of spring recoil such means must be active before the start of spring recoil; if the speed governing means do not start or become active until after the beginning of 50 spring recoil, then the check to such spring recoil produces an unpleasant jar.

It will be obvious to those skilled in the art that various changes may be made in my device without departing from the spirit 55 of the invention and therefore I do not limit myself to what is shown in the drawings and described in the specification but only as indicated in the appended claims.

Having thus fully described my said invention, what I claim as new and desire to secure by Letters Patent is:

1. In a shock diffuser, a chamber adapted to be fixed to the body of a vehicle said chamber containing a body of liquid, a fixed 60 depending yoke extending below the level

of the liquid, a piston on said fixed yoke, a movable cylinder for said piston having its lower rim below the level of said liquid, and connections from said cylinder to the running gear of the vehicle, substantially as 70 set forth.

2. In a shock diffuser, a chamber adapted to be fixed to the body of a vehicle said chamber containing a body of liquid, a fixed depending yoke extending below the level 75 of the liquid, a piston on said fixed yoke, a movable cylinder for said piston having its lower rim below the level of said liquid, connections from said cylinder to the running gear of the vehicle, and means adjacent 80 individual joints in said connections acting in the direction of transmission of a spring recoil for preventing lost motion in said joints, substantially as set forth.

3. In a shock diffuser, a chamber adapted 85 to be fixed to the body of a vehicle said chamber containing a body of liquid, a fixed depending yoke extending below the level of the liquid, an apertured piston on said fixed yoke, a movable cylinder for said piston having its lower rim below the level of said liquid, a valve closing the aperture in the piston during relative approaching movement of the cylinder and piston, and connections from said cylinder to the running gear of the vehicle, substantially as 95 set forth.

4. In a shock diffuser, a housing, journals mounted for oscillation in bearing openings in the walls of said housing, a rockarm between said journals, means securing the rockarm and the journals together, and a movable shock-diffusing element carried by said rockarm, substantially as set forth.

5. In a shock diffuser, a housing, a pair 105 of disks mounted to oscillate in bearings on the housing, a rockarm between adjacent faces of said disks, and a movable shock-diffusing element on said rockarm, substantially as set forth.

6. In a shock diffuser, a housing, a pair of disks mounted to oscillate in bearings on the housing, a rockarm between adjacent faces of said disks, a plurality of pins connecting said disks and rockarm together for 115 oscillation, and a movable shock-diffusing element on said rockarm, substantially as set forth.

7. In a shock diffuser, a housing, a pair of disks mounted to oscillate in bearings on the housing, a rockarm between adjacent faces of said disks, a plurality of pins connecting said disks and rockarm together for oscillation, a bolt extending axially of said disks, washers on said bolt engaging the ends of the pins outside the housing, and a movable shock-diffusing element on said rockarm, substantially as set forth.

8. In a shock diffuser, a housing, a pair 120 of disks mounted to oscillate in bearings on

the housing, a rockarm between adjacent faces of said disks, pins connecting the disks to the rockarm, levers on said pins outside the housing, and means to hold the levers in place, substantially as set forth.

9. In a shock diffuser, a housing, a pair of disks mounted to oscillate in bearings on the housing, a rockarm between adjacent faces of said disks, pins extending through said disks and rockarm beyond said housing, means at the ends of the journals to exclude dust from the bearings, and levers mounted on the outer ends of said pins, substantially as set forth.

10. In a shock diffuser, a housing adapted to be secured to the frame of a vehicle, a container for a body of fluid below the housing, a yoke on the housing extending into the container, a shock diffusing element carried by the housing movable in said body of fluid and a co-operating shock diffusing element carried by said yoke, substantially as set forth.

11. In a shock diffuser, a housing adapted to be secured to the frame of a vehicle, a container for a body of fluid below the housing a yoke on the housing extending into the container, a cylinder and a piston carried by said yoke and said housing respectively, and connections from one of said elements to the running gear of said vehicle, substantially as set forth.

12. In a shock diffuser, a janus-faced housing adapted to be secured to either side 35 of the frame of a vehicle, a container for a body of fluid below the housing, a yoke on the housing extending into the container, a cylinder carried by the housing, a piston pivoted on the yoke, and connections from 40 the cylinder to the running gear for moving the cylinder toward the piston to check the recoil of the vehicle springs, substantially as set forth.

13. In a shock diffuser, a housing adapted to be secured to the frame of a vehicle, a container for a body of liquid below the housing, a yoke on the housing extending into the container, a cylinder carried by the housing with its lower margin below the 50 level of said body of liquid, a piston pivoted on the yoke, and connections from the cylinder to the running gear for moving the cylinder toward the piston to check the recoil of the vehicle springs, substantially as 55 set forth.

14. In a shock diffuser, a housing for attachment to a vehicle body or the like, means to support a body of oil below the housing, a journal in the housing, a shock diffusing element supported by said journal, said element contacting with said liquid, a pipe extending from said oil up to said journal, and means to force oil through said pipe to said journal, substantially as set forth.

15. In a shock diffuser, a housing for at-

tachment to a vehicle body or the like, means to support a body of oil below the housing, a journal in the housing, a shock diffusing element supported by said journal, and means to force oil to said journal from said body 70 of oil, substantially as set forth.

16. In a shock diffuser, a housing, a container for a body of liquid beneath the housing, a rockarm journaled in the housing, an inverted reciprocating cylinder on the rock-arm depending into said body of liquid, a bypass pipe leading down from the closed end of the cylinder, a piston co-operating with the cylinder, a funnel below the upper surface of a body of liquid said funnel located within the downward current from said bypass pipe, and a pipe leading from the funnel to a point adjacent the bearings for the rockarm for lubricating them, substantially as set forth.

17. In a shock diffuser, a housing, a container for a body of liquid beneath the housing, a rockarm journaled in the housing, a shock-diffusing element on said rockarm coacting with said liquid, a pluralized or 90 double lever straddling the housing and fixed to said rock arm, and a pivoted link connecting the free end of said lever to the running gear of the vehicle, substantially as set forth.

18. In a shock diffuser, a housing, a container for a body of liquid beneath the housing, a rockarm journaled in the housing, a shock diffusing element on said rockarm coacting with said liquid, a lever fixed to said rockarm, a link pivoted at one end to said lever and at the other to an unsprung part 100 of the vehicle, and means to maintain contact of the pivots and the parts connected thereby in the direction of the force exerted 105 on a recoil of the vehicle springs, substantially as set forth.

19. In a shock diffuser, a housing, a container for a body of liquid beneath the housing, a rockarm supported between two journals in the housing, a shock-diffusing element on said rockarm coacting with said liquid, levers fixed to said journals and rock-arm, a rigid rod pivoted at one end to said levers and at the other to an element of the 110 axle of the vehicle, coil springs at each end of the rod acting in the direction of the force produced on recoil of a vehicle spring 115 to maintain contact of said pivots, and blocks between the ends of the springs and the adjacent rocking surfaces, substantially as set forth.

20. In a shock diffuser, a unit housing which is janus-faced, and constitutes a base to which all other details are directly or indirectly attached in combination with a liquid retainer which is suspended from said housing, and a hinged bail or hanger for holding said retainer in place, substantially as shown and described.

21. In a shock diffuser, a janus-faced housing adapted to be attached to either side of the frame or body of a vehicle, a container for a body of liquid below the housing said container being in contact with said housing around the lower margin of the same forming a slip joint, and a yoke pivoted to the housing which supports said liquid container, substantially as set forth.
- 5 22. In a shock diffuser, a unit housing forming a base for all apparatus details, in combination with a liquid retainer attached to the bottom of said housing by a slip joint, and a swing bail jointed to said housing for supporting said retainer, substantially as set forth.
- 10 23. In a shock diffuser, a housing for attachment to a vehicle body or the like, means to support a body of oil below the housing, a journal in the housing, a shock diffusing element supported by said journal, a pipe leading from said body of oil to said journal, and means to force oil through said pipe to said journal, substantially as set forth.
- 20 24. A hydraulic shock diffuser comprising a janus-faced housing adapted for rigid attachment to either side of an automobile body adjacent to either end thereof, a container for a body of liquid carried by said housing, a shock diffusing element movable in said liquid, and connections from said element to an unsprung part of the automobile, substantially as set forth.
- 25 25. A hydraulic shock diffuser comprising a janus-faced housing adapted for rigid attachment to either side of an automobile body adjacent to either end thereof, a quickly detachable container for a body of liquid carried by said housing, a shock diffusing element movable in said liquid, and connections from said element to an unsprung part of the automobile, substantially as set forth.
- 30 26. A hydraulic shock diffuser comprising a housing adapted for rigid attachment to a vehicle, a container for a body of liquid, quickly detachable means for holding said container in place on said housing, shock diffusing means movable in said body of liquid, and connections from said means to an unsprung element of the vehicle, substantially as set forth.
- 35 27. A hydraulic shock diffuser comprising a housing adapted to be secured rigidly to an automobile body, means in connection with the housing for retaining a body of liquid, a shock diffusing element movable in said body of liquid, bearings at opposite sides of said housing, a journal in said bearings forming an unpacked joint with the housing, connections from the journal to the shock diffusing element, levers secured to said journal, and connections from said levers to an unsprung element of the automobile, substantially as set forth.
- 40 28. In a shock diffuser a cylinder, a piston within said cylinder of a diameter slightly less than the inside diameter of said cylinder whereby a thin annular passage around said piston is provided, and a tube leading from the closed end of said cylinder which in connection with said annular passage around said piston constitutes a liquid by-pass from the cylinder whereby the liquid violently discharged during the auto spring recoil from said pipe and said annular passage passes beneath a body of liquid in which said cylinder is partly submerged, substantially as set forth.
- 45 29. A hydraulic shock diffuser comprising a reciprocating cylinder in combination with an oscillating piston therein the open end of said cylinder being submerged in a body of liquid, substantially as set forth.
- 50 30. A hydraulic shock diffuser comprising a cylinder, a piston fitting freely therein, and means for directing the liquid discharge from the cylinder on the compression stroke downward and beneath the surface of a body of liquid, substantially as set forth.
- 55 31. In witness whereof, I have hereunto set my hand and seal at Waynesboro, Pennsylvania, this 6th day of October, A. D. nineteen hundred and twenty-four.
